US00D816103S

(12) **United States Design Patent** (10) **Patent No.:** **US D816,103 S**
Lim (45) **Date of Patent:** **** Apr. 24, 2018**

(54) **DISPLAY SCREEN OR PORTION THEREOF WITH GRAPHICAL USER INTERFACE**

(71) Applicant: **SAMSUNG ELECTRONICS CO., LTD.**, Suwon-si, Gyeonggi-do (KR)

(72) Inventor: **Dongkyu Lim**, Seoul (KR)

(73) Assignee: **SAMSUNG ELECTRONICS CO., LTD.**, Gyeonggi-Do (KR)

(**) Term: **15 Years**

(21) Appl. No.: **29/562,105**

(22) Filed: **Apr. 22, 2016**

(30) **Foreign Application Priority Data**

Jan. 22, 2016 (KR) 30-2016-0003423

(51) **LOC (11) Cl.** **14-04**

(52) **U.S. Cl.**

USPC **D14/486**

(57) **CLAIM**

The ornamental design for a display screen or portion thereof with graphical user interface, as shown and described.

DESCRIPTION

FIG. 1 is a front view of a display screen or portion thereof with graphical user interface according to a first embodiment, showing my new design;

FIG. 2 is a front view thereof according to a second embodiment;

FIG. 3 is a front view thereof according to a third embodiment; and,

FIG. 4 is a front view thereof according to a fourth embodiment.

The outermost broken lines illustrate a display screen or portion thereof. The remaining broken lines illustrate portions of the graphical interface. None of the broken lines form part of the claimed design.

1 Claim, 4 Drawing Sheets
